G. A. WELCH,
ASH DUST REMOVER,
FILED MAR. 11, 1921.

FIG 2

INVENTOR:

George A. Welch
BY
Pierre Barnes
ATTORNEY

UNITED STATES PATENT OFFICE.

GEORGE A. WELCH, OF SEATTLE, WASHINGTON.

ASH-DUST REMOVER.

Application filed March 11, 1921. Serial No. 451,450.

To all whom it may concern:

Be it known that I, GEORGE A. WELCH, a citizen of the United States, residing at Seattle, in the county of King and State of Washington, have invented certain new and useful Improvements in Ash-Dust Removers, of which the following is a specification.

This invention relates to ash-dust collectors and conveyors; the object of my invention is the provision of a device of this character attached to the smoke pipe of a heating-furnace and which is adapted to be applied to the top of an ash-can for removing the dust therefrom by the natural draft obtaining in the smoke pipe.

A further object of the invention is the provision in a dust-conveyor of means rendered operable through the medium of the hood to regulate the conveyor passage so as not to interfere with the draft in the associated smoke pipe.

The invention consists in the novel construction, adaptation and combination of parts as will be hereinafter described and claimed.

In the accompanying drawings,—

Figure 1 is a view, partly in front elevation and partly in vertical section, of devices embodying my invention, shown applied. Fig. 2 is a front elevation illustrating the attachment for an ash-can and the pipe connection therefor.

In said drawings, the reference numeral 5 designates a boiler or furnace such, for example, as employed for domestic heating and is provided with a smoke pipe 6 leading to a chimney or stack. 7 represents a cylindrical ash-can of the type conventionally known as a "garbage-can" which, as shown, is supported upon a wheeled vehicle 8 to render said can conveniently portable.

According to the present invention, for the can 7 I provide a truncated conical cover or hood 9. Adjacent to one of its sides said hood has extending therethrough a chute 10 formed and arranged substantially, as shown.

Adjacent to the side opposite to the chute 10, said hood is provided with an opening 11 into a pipe 12 which is rigid with and extends upwardly from said hood.

The pipe 12 is sleeved within the lower end of a pipe 13 which is rigidly connected by an elbow 14 to the smoke pipe 6.

The pipes 12 and 13 constitute members

of an ash-dust conveyor and by being telescopically connected afford vertical movement to said hood for removably seating the same upon the ash-can.

A rod 15 extends diametrically through the pipe 12 into vertical guide slots 16 provided in the pipe 13 to accommodate the vertical movement of the hood.

By turning the hood to cause the ends of the rod 14 to lodge in notches, such as 16¹, at the upper ends of the respective slots said hood is retained in its elevated position for the removal of an ash-can or during the absence of the same from below the hood.

17 represents a damper provided in the pipe 13 to close the latter when the hood is disconnected from a can.

As shown, an arm 18 provided on an end of the damper spindle is pivotally connected to an end of a link 19 which extends through an aperture in one of the ends of the rod 15.

The lower portion of the link 19 is screw threaded to receive nuts 20 and 21 which are respectively disposed above and below the rod 15.

A helical spring 22 provided on the link between the nut 21 and said rod affords limited downward motion to the hood after the damper has been arrested in its full open position by the arm 18 thereof encountering a stop 23 provided on the pipe.

By means of the damper controlling devices above described, it will be apparent that the damper is closed and opened respectively by raising and lowering the hood. The spring yielding enables the hood to be moved to varying distances to suit cans of various diameters and heights. 95 A reinforcing band or collar 25 is advantageously provided about the lower end of pipe member 13.

The operation will be understood from the foregoing description. When the hood is engaged upon an ash-can, the damper is open and the draft occurring in the smoke pipe 6 will create suction through the pipe members 12 and 13 to draw ash dust into said smoke pipe when ashes are shoveled or dumped through the chute 10 into the ash-can.

What I claim, is,—

1. In apparatus of the character described, the combination with an ash-recep-

- tacle and a removable cover therefor provided with an ash receiving chute, of a dust-conveying pipe formed of two telescopically arranged members, one of said members being rigid with said cover, means connecting said pipe members for relative longitudinal and rotary movements, said means serving to releasably support said cover at a distance above the height of said receptacle, a damper provided in said pipe, means rendered operative by the lowering of said cover onto and from said receptacle to respectively effect the opening and closing movements of said damper, and means associated with said damper for resiliently supporting said cover when the damper is in an open position.
2. In apparatus of the character described, the combination with an ash receptacle, of a vertically arranged dust conveying pipe comprising two members telescopically connected together, a cover for an ash receptacle suspended by the lower of said members, a damper in the upper of said members, means operatively connecting the lower of said members with said damper whereby the latter is moved into open and closed position in the downward and upward movements respectively of said cover, said means comprising a cross bar within the lower of said members, one end of which projects through a slot in the upper of said members, and a connecting rod between the projecting end of said cross bar and a link member operatively associated with said damper.
3. An apparatus of the character described, wherein the smoke outlet pipe of a furnace has a depending pipe section carried thereby, an ash can hood resiliently supported on the lower end of the pipe section and permanently connected thereto.
4. An apparatus of the character described, wherein the smoke outlet pipe of a furnace has a depending pipe section carried thereby, an ash can hood resiliently supported on the lower end of the pipe section and permanently connected thereto, and a filling spout projecting upwardly from said hood.
5. An apparatus of the character described, wherein the smoke outlet pipe of a furnace has a depending pipe section carried thereby, an ash can hood resiliently supported on the lower end of the pipe section and permanently connected thereto, and a damper valve pivotally mounted in the depending pipe section and associated with the resilient support for said hood adapted for automatically closing when the hood is lowered.

Signed at Seattle, Washington, this 25th day of February 1921.

GEORGE A. WELCH.
